(57) **CLAIM**

The ornamental design for a heat reflector for semiconductor manufacturing equipment as shown and described.

DESCRIPTION

FIG. 1 is a front, top and right side perspective view of a heat reflector for semiconductor manufacturing equipment, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view taken along line 8-8 in FIG. 2; and,

FIG. 9 is an enlarged portion view taken from the encircled portion, labeled "FIG. 9," in FIG. 8.

The dot-dashed lines show the boundary of the enlarged portion view of FIG. 9 in FIGS. 8 and 9, and form no part of the claimed design.

The surface members shown in FIGS. 1 and 2 are made of a transparent material with a mirror finish inside the frame of the transparent material.
